UNITED STATES PATENT OFFICE.

ISAAC H. GIFFING, OF NEW YORK, N. Y.

MODE OF ATTACHING CASTERS TO TRUNKS.

Specification of Letters Patent No. 23,672, dated April 19, 1859.

To all whom it may concern:

Be it known that I, ISAAC H. GIFFING, of the city and county of New York and State of New York, have invented a new and 5 Improved Caster for Trunks or Boxes; and I do hereby declare that the following is a full and exact description, to wit:

The nature of my invention consists in providing a sufficient space between the plate 10 and roller so that a band or strap of metal (such as is now in use for strengthening trunks or boxes) may be passed freely between the plate and roller, also making a flange continuously along the whole length 15 of both sides of the plate in order to prevent the plate from twisting and also for the purpose of additional strength.

To enable others skilled in art to make 20 and use my invention, I will proceed to describe its construction and operation.

I take a plate of iron or other strong metal about $\frac{1}{16}$ of an inch in thickness about 25 3 inches long and about $2\frac{1}{2}$ inches wide. I then mark two parallel lines along said plate lengthwise about $\frac{3}{4}$ of an inch from each edge see drawing No. 1. I then bend the plate at right angles along both lines and in the same direction so as to form a flange 30 about $\frac{3}{4}$ of an inch high on both sides (or edges). I then mark off a line about $\frac{1}{2}$ an inch from one end and sloping downward toward the back of the plate so as to leave a flange $\frac{3}{4}$ of an inch high at one end and $\frac{1}{16}$ of an inch high at the other, see drawing 35 No. 2. I then cut or file both flanges according to said sloping lines and file the highest part of the flange circular at the end, see drawing No. 2. I then drill two or more holes in the center part or back of the plate

(for the purpose of fastening it on the 40 trunk or box). I then drill a hole through the highest part or end of both flanges near the edge and so as to raise the roller from the back of the plate a sufficient distance to allow the strap or band (before mentioned) 45 to pass along between the two flanges and also beneath the roller and between it (the roller) and the plate freely, the roller being placed between the flanges so as to project beyond the edges of the flange a sufficient 50 distance. I now pass a strong wire through the two flanges and roller, riveting both ends of said wire firmly, see drawing No. 3, or I may cut the plate of iron aforesaid in proper shape and then bend the flanges or 55 else I may mold and cast the plates in the shape or form all as before described. The before mentioned dimensions are to be varied according to the size or strength required. The manner of using said caster is, 60 to rivet, nail or screw the plate (through the holes in the back) on the trunk or box then pass the strap or band between the flanges, beneath the roller and between that and the plate, then bend the strap up to the side or 65 end of the trunk and fasten there firmly by nailing or screwing or they may be both fastened together at one time.

I do not claim the roller or strap separately as they have been used on trunks for 70 many years.

What I do claim is,

The method herein described of constructing and attaching casters to trunks.

I. H. GIFFING.
